UNITED STATES PATENT OFFICE

2,440,793

GREASE INTERCEPTOR

Edward W. N. Boosey, Detroit, Mich.

Application August 4, 1945, Serial No. 608,879

6 Claims. (Cl. 182—9)

1

This invention relates to grease interceptors the object being to provide a new and improved structure wherein the water containing oil and grease discharging therewith is caused to separate the oil and greases from the water and water only can be discharged through the outlet into the sewer with which it is connected.

These and other features and objects of the invention are hereinafter more fully described and claimed and the preferred form of grease interceptor embodying my invention is shown in the accompanying drawing in which:

Fig. 1 is a perspective view of my improved grease interceptor.

Fig. 2 is a vertical section of the inlet column taken on line 2—2 of Fig. 1.

Fig. 3 is a vertical section of the outlet column.

In its preferred form the interceptor is rectangular in cross section and plan view and has at one end of the body and therewithin a vertical conduit 1 preferably of rectangular form in cross section and having an inlet 2 for connection with the conduit positioned intermediate the ends thereof. The wall 3 of the conduit 1 opposite the inlet 2 is inwardly inclined in respect to the vertical and its lower end extends to a point forward of the adjacent side of the interceptor. Thus liquid containing oils and greases tends to be deflected upwardly by the wall 2 and through the open upper end thereof providing an opportunity for separation of the oils and greases from the water discharging therewith from the inlet. This arrangement enables the lighter elements in the waste liquid to rise to the top and discharge therefrom through the extension 4 at the upper end of the inlet column.

The heavier liquids pass downwardly through the lower end 5 of the inlet member which extends inwardly and downwardly at an angle to the vertical. Water passes through the opening 6 at the lower end of the inlet and passes between the shield 7 and the adjacent side of the interceptor body as shown in Fig. 2.

At the same end of the body is provided an outlet column 9 in spaced relation with the inlet 1 and the column 9 has an outlet conduit 10 connected therewith adjacent the top and provides for discharge of liquid from the body.

The body of the interceptor has an upwardly inclined wall 11 at one end and above and in spaced relation with the said wall 11 is a series of plates 12 vertically positioned in spaced parallel relation with the inclined wall at the bottom as shown in Fig. 1. The interceptor has a recessed removable cover 13 to permit access to

5 and inspection of the interior of the body. The recessed cover provides an air space at the top of the body. The outlet column 9 has an open ended tubular element 14 opening to the air space above the liquid level.

On discharge of water containing oils and greases into the inlet column it flows into the body between the shield 7 and the side wall adjacent the inlet column and the oil and greases 10 may rise to the surface of the water between the spaced plates 12. The shield prevents flow of liquid laterally across the bottom of the body from the inlet to the outlet column.

This column 9, as shown in Fig. 3, is formed at 15 its upper end with an upwardly extending tubular portion 14 open to the air space above the liquid body in the interceptor. The upper end of the outlet column is of greater area in cross section than the main body portion thereof and 20 has a vertical dividing wall 15 therein opposite the outlet 10 of the outlet column 9 and a horizontal wall extending transversely of the head of the column as indicated at 16. The horizontal wall 16 has an opening 17 to permit air to flow 25 from the air and gas space at the top of the interceptor body to the outlet. When the liquid level in the interceptor body rises a sufficient distance above the lower end of the outlet tube 14 liquid may pass through the opening 17 to the outlet. Also when a volume of air accumulates 30 in the top of the body sufficient to lower the liquid level in the interceptor body below the lower end of the vent tube 14, it may discharge through the outlet 10 connected to the sewer. Preferably 35 the vent tube 14 extends downwardly into the outlet conduit 9 to below the horizontal wall 16 adjacent the top thereof.

By the arrangement of parts described a simple and efficient device is provided to separate the 40 oils and greases from the inflowing body and prevent discharge thereof to the outlet.

It is believed evident from the foregoing that the various objects and features of the invention are obtained by the described relationship of 45 parts.

Having thus briefly described my invention, its utility and mode of operation, what I claim and desire to secure by Letters Patent of the United States is:

50 1. A grease interceptor comprising a chambered body of rectangular form in cross section and having a bottom wall provided at one end with a troughlike portion below the level of the bottom wall, an inlet column at said end of the body having an opening intermediate its ends to

receive an inlet conduit, the wall of the body opposite the inlet opening having an upwardly inclined portion at its lower end tending to deflect liquid upwardly thereby providing a time interval for greases to rise, the inlet column having an opening at its upper end to the interior of the body through which the lighter liquids in the upper end thereof may flow into the upper portion of the liquid in the body, the lower end of the inlet column having an opening at its bottom through which inflowing liquid is discharged across the bottom of the body, the wall of the body opposite the inlet end having an upwardly inclined portion, a series of baffle plates positioned thereabove in spaced relation with the lower ends spaced from the inclined wall providing a means permitting the oil to separate from the heavier liquids as it flows across the inclined portion of the bottom, an outlet column on the same side of the body as the inlet column and in spaced relation transversely of the body, and means associated with the inlet column directing the flow of liquid discharging thereto across the bottom of the body and to thereafter flow in the opposite direction to the outlet, a cover for the body forming an air chamber above the liquid level in the body, and means for venting said chamber to the outlet to thereby prevent accumulation of pressure on the liquid in the body.

2. A grease interceptor comprising a chambered body of rectangular form in cross section and having a bottom wall formed at one end to provide a troughlike portion below the level of the bottom wall and adjacent to and parallel with a vertical side wall, an inlet column within the body at said end having an outlet at its lower end through which liquid may discharge across the bottom wall toward the opposite side wall of the body, said bottom wall having a portion thereof upwardly inclined toward said opposite side wall, a series of vertically positioned and horizontally spaced plates having the lower ends in spaced relation with said upwardly inclined portion, said plates providing a means restricting the rapidity of flow of liquid across the bottom thereby providing a time interval permitting oil and grease in the inflowing liquid to rise between the plates to the surface of the liquid in the interceptor body, and an outlet column positioned to permit liquid from the bottom of the body to discharge from the interceptor.

3. A grease interceptor comprising a chambered body of rectangular form in cross section and having a bottom wall formed at one end to provide a troughlike portion below the level of the bottom wall and adjacent to and parallel with a vertical side wall, an inlet column within the body at said end having an outlet at its lower end through which liquid may discharge across the bottom wall toward the opposite side wall of the body, said bottom wall having a portion thereof upwardly inclined toward said opposite side wall, a series of vertically positioned and horizontally spaced plates having the lower ends in spaced relation with said upwardly inclined portion, said plates providing a means restricting the rapidity of flow of liquid across the bottom thereby providing a time interval permitting oil and grease in the inflowing liquid to rise between the plates to the surface of the liquid in the interceptor body, an outlet column positioned to permit liquid from the bottom of the body to discharge from the interceptor, said bottom wall at the inlet side of the body having a trough like portion at and parallel with the inlet side of the body, and said outlet

let column opening at its lower end to said troughlike portion below the bottom wall.

4. A grease interceptor comprising a chambered body of rectangular form in cross section and having a bottom wall formed at one end to provide a troughlike portion below the level of the bottom wall and adjacent to and parallel with a vertical side wall, an inlet column within the body at said end having an outlet at its lower end through which liquid may discharge across the bottom wall toward the opposite side wall of the body, said bottom wall having a portion thereof upwardly inclined toward said opposite side wall, a series of vertically positioned and horizontally spaced plates having the lower ends in spaced relation with said upwardly inclined portion, said plates providing a means restricting the rapidity of flow of liquid across the bottom thereby providing a time interval permitting oil and grease in the inflowing liquid to rise between the plates to the surface of the liquid in the interceptor body, an outlet column positioned to permit liquid from the bottom of the body to discharge from the interceptor, said outlet column including a means to vent the air space at the top of the liquid body to the outlet.

5. A grease interceptor comprising a chambered body of rectangular form in cross section and having a bottom wall formed at one end to provide a troughlike portion below the level of the bottom wall and adjacent to and parallel with a vertical side wall, an inlet column within the body at said end having an outlet at its lower end through which liquid may discharge across the bottom wall toward the opposite side wall of the body, said bottom wall having a portion thereof upwardly inclined toward said opposite side wall, a series of vertically positioned and horizontally spaced plates having the lower ends in spaced relation with said upwardly inclined portion, said plates providing a means restricting the rapidity of flow of liquid across the bottom thereby providing a time interval permitting oil and grease in the inflowing liquid to rise between the plates to the surface of the liquid in the interceptor body, an outlet column positioned to permit liquid from the bottom of the body to discharge from the interceptor, and means associated with the outlet column preventing accumulation of air in the top of the body thereby maintaining the liquid in the body under atmospheric pressure.

6. A grease interceptor comprising a chambered body of rectangular form in cross section and having a bottom wall formed at one end to provide a troughlike portion below the level of the bottom wall and adjacent to and parallel with a vertical side wall, an inlet column within the body at said end having an outlet at its lower end through which liquid may discharge across the bottom wall toward the opposite side wall of the body, said bottom wall having a portion thereof upwardly inclined toward said opposite side wall, a series of vertically positioned and horizontally spaced plates having the lower ends in spaced relation with said upwardly inclined portion, said plates providing a means restricting the rapidity of flow of liquid across the bottom thereby providing a time interval permitting oil and grease in the inflowing liquid to rise between the plates to the surface of the liquid in the interceptor body, an outlet column positioned to permit liquid from the bottom of the body to discharge from the interceptor, and means for preventing liquid discharging into the body from the inlet column

from passing laterally across the bottom of the body to the outlet.
